ATTORNEY

UNITED STATES PATENT OFFICE.

MELVIN M. CONKLIN, OF ELMIRA, NEW YORK, ASSIGNOR OF ONE-HALF TO
CORNELIUS B. MATHER, OF ELMIRA, NEW YORK.

MAIL-BOX.

SPECIFICATION forming part of Letters Patent No. 694,053, dated February 25, 1902.

Application filed February 9, 1901. Serial No. 46,637. (No model.)

To all whom it may concern:

Be it known that I, MELVIN M. CONKLIN, a citizen of the United States, residing at Elmira, in the county of Chemung and State of New York, have invented a new and useful Improvement in Mail-Boxes, of which the following is a specification.

My invention relates more particularly to improvements in mail-boxes intended to be used in connection with the rural delivery-service, and has for its object to provide a weather-proof box of this nature in which the incoming and outgoing mail-matter may be kept separate and which shall be of simple and cheap construction and also wherein the incoming mail-matter may be locked to all except the owner of the box and the outgoing mail-matter to all except the postman, one key in the possession of the postman serving to unlock all the outgoing-mail compartments of all the boxes on his route and the incoming-mail compartments of the different boxes being controlled by different keys in the possession of their respective owners. I attain this object by means of a box arranged and constructed substantially in the manner illustrated in the accompanying drawings, in which—

Figure 1 represents a front elevation of the box with the weather-lid open; Fig. 2, a side elevation of the same; Fig. 3, a vertical transverse cross-section, and Fig. 4 a detail showing a signal attachment.

Similar letters refer to like parts throughout the several views.

A represents an oblong box, the ends of which are semicircular in form at the top, the box being provided at the front with an opening *a*, extending across the entire length of the box, and the back of the box being brought up over the curved top, as shown in Fig. 3.

B is a longitudinal partition, which divides the box into the two compartments C and D, the compartment C being accessible by way of the opening *a*, which opening is closed by the lid E, which conforms to the curve of the top of the box, and is pivoted at each side at *e e*. Access to compartment D is attained through compartment C by way of a door F, which is hinged at the lower side of a longitudinal slot in the partition B, this slot extending practi-

cally the full length of the box. A spring-lock G secures the door F when thrown up into vertical position, as indicated in Fig. 3. A staple *h* projects from the outer side of this door, so that when it is thrown down into the position indicated in the broken lines at F' in Figs. 1 and 3 it will be locked in that position by means of a spring-lock H. The bottom *b* of the box is slightly raised, thereby providing a depending flange around the entire box, whereby it may be attached to a post or other support.

J represents a signal-plate which is pivoted to a rod I, attached to the lid E at the uppermost portion thereof when the lid is in closed position, as shown in Fig. 3. A wire standard L, bent into the form shown, serves to hold the signal-plate in an upright position when the plate is thrown up into a vertical position, this being accomplished by sliding the plate along the bar I between the lips of the standard L.

In operation the owner of the box if he has mail to be taken up by the letter-carrier will place such mail-matter in the bottom *c* of the compartment C, at the same time unlocking the door F and throwing it down into the position indicated at F', in which position it becomes locked by means of the lock H, and no one except the letter-carrier who holds the key to this lock can then get at this mail. The lid E is then thrown down, and the contents of the box are thereby thoroughly protected from inclemency of the weather. At the same time the owner throws up the signal-plate J into the position shown in Fig. 3, thereby notifying the letter-carrier that there is mail-matter to be taken up from the box. If the letter-carrier has mail for the owner of the box, he places such mail-matter in the compartment D and throws up the cover F into its vertical position, thereby locking the incoming mail-matter in the compartment D and disclosing the outgoing mail, which he then removes, closing the lid E and leaving the signal-plate J in its elevated position to indicate to the owner that there is mail in the box for him. If the postman has no mail for the box, after removing the outgoing mail he will throw the signal-plate J down after closing the lid E.

While I have shown two locks for this box, the lock H may be omitted and only the compartment D provided with a lock, the key to which will be in possession of the owner, thereby relieving the postman of the necessity of carrying a key, but at the same time leaving the contents of the outgoing-mail compartment unlocked. Also instead of placing the outgoing mail in the subcompartment c it may be placed on top of the door when thrown into the position F', in which case the postman will take out the outgoing mail-matter before placing the incoming mail-matter in the compartment D, and in which case also the depth of the box may be lessened, thereby doing away entirely with the subcompartment c. The box may be made of any suitable material. As illustrated, it is formed of sheet metal, such as galvanized iron; but it may equally well be made of cast iron, if so desired.

Having thus described my improvements, what I claim as my invention, and desire to secure by Letters Patent, is—

25 1. A mail-box comprising an inner and an outer compartment, a longitudinal partition separating said compartments, an aperture in said partition through which mail-matter is deposited in and removed from the inner compartment by way of the outer compartment, said inner compartment being otherwise closed, a door for said aperture provided with a spring-lock and a closure for the outer compartment, whereby mail deposited in the 30 outer compartment may be taken therefrom

35 by the mail-carrier, but mail deposited in the inner compartment by the carrier can only be removed therefrom by the possessor of the key to said lock.

2. A mail-box comprising an inner and an outer compartment, a longitudinal partition separating said compartments, an aperture in the upper part of said partition through which mail-matter is deposited in and removed from the inner compartment by way of the outer compartment, said inner compartment being otherwise closed, a door for said aperture hinged at its lower edge, said door opening into the outer compartment and when thrown down into a horizontal position 45 closing off a subcompartment therein, separate spring-locks for locking said door in its vertical and horizontal positions respectively, as and for the purpose set forth, and a closure for the outer compartment.

3. In a mail-box of the type described, the combination, with the curved lid, of a signal-plate hinged upon a rod attached to and running parallel with the top of the lid at its uppermost edge when in closed position, said 50 plate being slidable upon said rod, and a forked standard rising from the lid to receive said plate when in elevated position.

In testimony whereof I have affixed my signature in presence of two witnesses.

MELVIN M. CONKLIN.
